UNITED STATES PATENT OFFICE

1,925,676

VENDING MACHINE

Myron H. Richardson, Chicago, Ill., assignor to
Advance Machine Company, Chicago, Ill., a
corporation of Illinois

Application October 26, 1929. Serial No. 402,586

13 Claims. (Cl. 312—67)

This invention relates to improvements in vending machines, of the check controlled type, and one of the objects of the same is to provide an improved machine of this character embodying a plurality of containers for the articles and improved ejecting means whereby the articles from one of the containers will be vended or dispensed in advance of the articles from the other container.

10 A further object is to provide improved ejecting means individual to the containers but common to the same operating mechanism, the ejecting means for one of the containers being rendered inactive and maintained inactive with respect to 15 delivering or ejecting articles from its particular container, by the presence of an article or articles in the other container, the inactive ejecting means being automatically rendered active in the absence of an article in the said other 20 container.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

25 Figure 1 is a view partly in elevation, partly broken away and with parts omitted and as taken from the rear of a machine of this character constructed in accordance with the principles of this invention and as also taken on line 1—1, Figure 2.

30 Figure 2 is a detail sectional view taken on line 2—2, Figure 1.

Figure 3 is a detail horizontal sectional view taken on line 3—3, Figure 1.

35 Figure 4 is a view similar to Figure 1, showing the normal position of the parts.

Figure 5 is a sectional view taken on line 5—5, Figure 4.

40 Figure 6 is a view similar to Figure 4, showing the position which the parts of the ejecting mechanism will assume when the articles have been entirely vended from one of the containers.

Figure 7 is a sectional view taken on line 7—7, Figure 6.

45 Figure 8 is a perspective view of the ejecting means showing the parts in the position which they will assume when ejecting the articles from the first container.

Figure 9 is a view similar to Figure 8, showing 50 the parts of the ejecting means in the position

they will assume when ejecting the articles from the other container.

Figure 10 is a rear elevation of a modified form of the invention.

Figure 11 is a detail perspective view of the 60 ejecting means shown in Figure 10.

Referring more particularly to the drawings the numeral 15 designates generally a casing of any desired size and configuration and in which casing are arranged two containers 16—17 in 65 which the articles 18 and 19 are arranged.

The casing is provided with a discharge outlet 20 through which the articles are delivered to the operator.

Arranged within the casing and at a suitable 70 point is a supporting platform 21 upon which is reciprocably mounted a slideable member 22 being held in position in any suitable manner, preferably by flanging the edges 23 thereof over the edges of the support 21 (see particularly Figure 1). 75

This member 22 is adapted to be reciprocated in any desired or suitable manner by means of check controlled mechanism also of any suitable construction.

The specific construction, however, of the check 80 controlled mechanism forms no part of the present invention. Suffice it to say that the check controlled mechanism is provided with an operating handle 24 which upon the insertion of a proper check into the machine through an opening 25 will form an operative connection between the handle 24 and a cam device 26 to rotate the latter. This cam device operates upon projections 27—28 on a member 29 that is pivotally supported as at 30. The member 29 is provided with

85 arms 31 which extend into openings 32 in an ear or projection 33 connected to the slideable member 22 so that when the cam device 26 is rotated it will alternately engage the projections 27—28 to rock the member 29 and thereby reciprocate 90 the member 22 upon its support.

Connected with the member 22 to reciprocate therewith is a fixed or rigid ejector 34 which is positioned beneath the container 16 to engage, when the ejector is in a proper position, behind 100 the lowermost article 18 to eject the latter upon the movement of the ejector 34 and the member 22 in one direction.

Pivotedly supported by the member 22 and in alignment with the ejector 34 is another ejector 105 35 which is arranged to operate beneath the container 17 to eject the articles 19 therefrom, similar to the manner in which the ejector 34 ejects the articles 18 from the container 16.

This ejector 35 is provided with a body por- 110

tion 36 which is shaped to form downwardly projecting ears 37 and is connected with upwardly projecting ears 38 on the member 22 and a pivot pin or rod 39 forms a pivotal connection between 5 the respective ears.

A spring 40 encompasses the pivot pin or rod 39 and tends normally to elevate or raise the ejector 35 to its uppermost position and to a position that it will pass behind the articles 19 in the 10 container 17 as shown more clearly in Figure 7.

Connected with the pivoted ejector 35 is an arm or finger 41 which is carried by a lateral extension of the ejector 35 and which extension preferably passes behind the ejector 34 as shown 15 more clearly in Figures 3 and 9. This extension or finger 40, when the ejector 35 is raised to its uppermost position with respect to the member 22 will project above the top of the ejector 34 and will be disposed beneath the articles 18 in the 20 container 16, as shown more clearly in Figures 4 to 7.

When there are any articles in the container 18 the arm or finger 41 will be depressed by the articles in the container 16 as shown in Figure 5, 25 so as to hold the ejector 35 depressed against the stress of the spring 40, with the result that when the ejector or supporting member 42 is reciprocated and articles are in the container 16, the ejector 35 will be prevented from ejecting the articles 19 from the container 17, as shown more clearly in Figures 4 and 5.

When, however, there are no articles in the container 16 the spring 40 will raise the ejector 35 to the position shown in Figures 6 and 7, so that the ejector 35 will pass behind the lowermost article 19 in the container 17, with the result that upon the next operation of the member 22 and the ejector 35 the lowermost article 19 from the container 17 will be ejected.

40 Upon the return movement of the member 22 and the ejecting means 35, when there are no articles in the container 16, the ejector 35 will be held depressed by reason of the engagement of the ejector under the lowermost article 19 in the 45 container 17, as shown in Figure 2 of the drawings, until the parts have assumed the position shown in Figure 7, at which time the spring 40 will raise the ejector 35 to a position to eject the lowermost article 19.

50 The check controlled mechanism which it is preferably desired to employ, is the one described in the aforesaid application and embodies in its mechanism a pivotally mounted member 42 having a finger 43 which is adapted to hold the check 55 against being discharged from the check carrying member of the check controlled mechanism when there are no articles in the container 17, and this is effected by reason of the fact that the member 42 is normally held by means of a spring 42^a in the position shown in Figure 3, so that the finger or projection 43 thereon will prevent the check from dropping out of its seat in the check carrier. Connected with this member 42 is an arm 44, which latter is connected with a rock 60 shaft or member 45 journaled in suitable bearings 46. Connected also with the shaft 45 is an arm or extension 47 which is bent upwardly as shown more clearly in Figure 7, towards and terminating beneath and in close proximity to the open 65 bottom of the container 17. The extremity 48 of the portion 47 of the shaft 45 may be bent as shown to prevent injury to the package.

The spring which holds the member 42 in the 70 position shown in Figure 3 is of sufficient strength 75 to rock the shaft 45 so as to elevate the end 48

of the shaft 45 to a sufficient height that when the articles 19 are in the container 17 the lowermost article will rest upon the end 48 to depress the latter and thereby move the member 42 in a direction to withdraw the finger 43 thereon so as to allow the check to drop from the check carrier and pass into the machine, as fully described in said application.

The normal position of the parts is as shown in Figures 4 and 5. That is when articles are in both the containers 16 and 17 the lowermost article in the container 16 will depress the arm or finger 41 on the ejector 35 and hold the latter depressed against the stress of the spring 40 and the ejector 34 will be disposed behind the lowermost package in the container 16. At the same time when articles are in the container 17 the lowermost article 19 will rest upon and depress the end 48 of the shaft 45 to rock the latter and withdraw the member 42 so as to permit the check to 95 pass into the machine, whereupon by the rotation of the handle 24 the member 22 carrying the elements 34 and 35 will be moved in the operative direction, with the result that the lowermost package will be ejected from the container 16 while the ejector 35 will be held in an inoperative position to pass under the lowermost article 19 in the container 17. This ejector 35 will be held depressed so long as there are any articles 18 in the container 16.

As soon as the container 16 is empty the spring 40 will raise the ejector 35 and the arm or finger 41 to the position shown in Figures 6 and 7, so as to permit the ejector 35 to assume a position back of the lowermost article 19 in the container 17. Whereupon, upon movement of the member 22 and the ejecting means supported thereby in an operative direction, the lowermost article 19 will be ejected from the container 17.

This operation may be continued until the container 17 is emptied, at which time the spring 42^a will move the member 42 in a direction to position the finger 43 so as to lock the check controlled mechanism against operation by reason of the fact that the end 48 of the shaft 45 will be permitted to rise.

Thus it will be seen that the vending of the articles from the container 17 will be controlled by the articles 18 in the container 16.

The bottom of the container 16 is preferably provided with supports 16^a, while the bottom of the container 17 is provided with supports 17^a, for supporting the articles.

If desired, weights or followers 49—50 may be provided in the containers 16 and 17 to insure the proper fitting movement of the respective articles therein.

In the form of the invention shown in Figures 10 and 11, there is disclosed three containers 51—52—53, although any number of containers 55 may be employed and arranged in substantially the same manner as shown in these two figures.

In Figure 10 the numeral 54 designates a fixed ejector corresponding to the ejector 34 in the other form of the invention. The numeral 55 corresponds with the member 36 which is pivotally mounted upon the reciprocating member 22 and is provided with an ejector 56 corresponding with the ejector 35 and a finger or projection 57 corresponding with the part 41, in the other form of the invention. This ejector 56 is adapted to operate beneath and eject the articles from the container 52. An additional ejector 57 is also pivotally mounted as at 58 with a reciprocating member 22 and is arranged to operate beneath and eject the 150

articles from the container 53. This ejector 57 is provided with a finger or projection 59 that is so arranged that it will operate beneath the articles in the container 52 to be depressed thereby so as to hold the ejector 57 in an inoperative position so long as there are any articles in the container 52.

It will therefore be manifest that with this form of the invention the articles in the container 51 control the discharge of the articles from the container 52, and likewise the articles in the container 52 control the discharge of the articles from the container 53 by respectively rendering the elements 56-57 inactive when there are any articles in the respective containers, but when there are no articles in the container 51, the ejector 56 will be rendered active and likewise when there are no articles in the container 52 the ejector 57 will be rendered active.

With this improved construction it will be manifest that a large supply of articles may be arranged in a very compact space and the machine will be automatically controlled in its operation by the presence or absence of the articles in the respective containers.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A vending machine embodying a plurality of containers for the articles to be vended, a delivery outlet, a reciprocable element, said element embodying ejectors individual to the containers, operating mechanism for said element, said ejectors being bodily movable with said element upon each operation of the latter, and one of said ejectors being also movable with respect to the other ejector, each of the ejectors operating to vend the articles in a single step of operation from the respective containers directly to said outlet, and means whereby the last said ejector will be rendered inactive with respect to the ejection of articles from its individual container, by the presence of articles in the other container.

2. A vending machine embodying a plurality of containers for the articles to be vended, a delivery outlet, a reciprocable element, said element embodying ejectors individual to the containers, each of the ejectors operating to vend the articles in a single step of operation from their respective containers directly to said outlet, operating mechanism for said element, said ejectors being bodily movable with said element upon each operation of the latter and one of said ejectors being also movable with respect to the other ejector, and means whereby the last said ejector will be rendered inactive with respect to the ejection of articles from its individual container, by the presence of articles in the other container and while the said other ejector remains active.

3. A vending machine embodying a plurality of containers for the articles to be vended, a delivery outlet, ejectors individual to the containers, operating means common to the ejectors for simultaneously actuating them upon each operation of the said operating means, one of said ejectors being relatively movable with respect to the other into and out of active position, each of the ejectors operating to vend the

articles in a single step of operation from the respective containers directly to said delivery outlet, means tending to normally cause the said relatively movable ejector to assume an operative position, and means responsive to the presence of an article in the container with which the said other ejector co-operates, to cause the said relatively movable ejector to be rendered inactive and against the stress of the second recited means.

4. A vending machine embodying a plurality of containers for the articles to be vended, a delivery outlet, a reciprocable element, means for reciprocating said element, ejectors individual to said containers and carried with said element for bodily movement therewith upon each operation of said element, each of the elements operating to vend the articles in a single step of operation from their respective containers directly to said delivery outlet, means adapting one of said ejectors for pivotal movement with respect to the other ejector and to said element whereby said pivoted ejector is adapted for movement into and out of active position, and means whereby the presence of an article in the container other than the container with which the said pivoted ejector co-operates, will cause the said pivoted ejector to be rendered inactive.

5. A vending machine embodying a plurality of containers for the articles to be vended, a delivery outlet, a reciprocable element, ejectors individual to the containers and bodily movable upon each operation of the said element, each of the ejectors operating to vend the articles from their respective containers directly to said delivery outlet, one of said ejectors being fixed with respect to the said element, means pivotally connecting the other ejector with the element for movement with respect thereto and into and out of active position with respect to its individual container, means tending normally to move the pivoted ejector with respect to said element and into an active position, and means connected with said pivoted ejector and extending into the path of movement of the articles in the other container for controlling the activity of the said pivoted ejector.

6. A vending machine embodying two containers for the articles to be vended, a delivery outlet, a reciprocable slide, means for actuating the slide, ejectors connected with the slide for bodily movement therewith upon each operation of the slide, said ejectors being individual to the containers and each operating to vend the articles in a single step of operation from their respective containers directly to the delivery outlet, means pivotally mounting one of the ejectors upon the slide for movement with respect thereto into and out of active position with respect to its container, means tending normally to move the last said ejector about its pivot into an active position, and means connected with the pivoted ejector and extending into the path of movement of the articles in the other container for moving the last said ejector against the stress of the last said means and into an inactive position.

7. A vending machine embodying two containers for the articles to be vended, a delivery outlet, a reciprocable slide, means for actuating the slide, ejectors connected with the slide for bodily movement therewith upon each operation of the slide, said ejectors being individual to the containers and each operating to vend the

- articles in a single step of operation from their respective containers directly to said delivery outlet, means pivotally mounting one of the ejectors upon the slide for movement with respect thereto into and out of active position with respect to its container, means tending normally to move the last said ejector about its pivot into an active position, and a finger connected with the said pivoted ejector and disposed in the path of movement of the articles in the other container for rendering the pivoted ejector inactive, said pivoted ejector being automatically rendered active in the absence of an article in the said other container.
15. 8. A vending machine embodying means for holding a plurality of supplies of articles side by side, a delivery outlet, a reciprocable slide, means for reciprocating the slide, a fixed ejector carried by the slide for vending the articles from one of said supplies directly to said delivery outlet, a pivoted ejector also carried by the slide for vending the articles from the other of said supplies and directly to said delivery outlet, means tending normally to move the pivoted ejector with respect to said slide into a position to eject the articles from its supply upon actuation of said slide, and means whereby the pivoted ejector will be moved into an inactive position with respect to its supply of articles by the presence of an article in the other supply.
9. A vending machine embodying means for holding a plurality of supplies of articles side by side, a delivery outlet, a reciprocable slide, means for reciprocating the slide, a fixed ejector carried by the slide for vending the articles from one of said supplies directly to said delivery outlet, a pivoted ejector also carried by the slide for vending the articles from the other of said supplies and directly to said delivery outlet, means tending normally to move the pivoted ejector with respect to said slide into a position to eject the articles from its supply upon actuation of said slide, and a finger connected with said pivoted ejector and extending into the path of movement of the articles in the other supply to be engaged and moved thereby for moving the pivoted ejector into an inactive position and for holding the same in such position during the presence of an article in said other supply.
50. 10. A vending machine for holding a plurality of supplies of articles side by side, a reciprocable element, a fixed ejector carried with said element, a pivoted ejector also carried with said element, an extension carried by the pivoted ejector and extending into the path of movement of the articles in the container individual to the fixed ejec-

tor, whereby the presence of articles in the last said container will render the pivoted ejector inactive, means tending normally to render the pivoted ejector active, the active faces of said ejectors being substantially in alinement and in substantially the same vertical plane, and means for reciprocating said element.

11. A vending machine for holding a plurality of supplies of articles side by side, a delivery outlet, a reciprocable element, a fixed ejector carried with said element, a pivoted ejector also carried with said element, an extension carried by the pivoted ejector and extending into the path of movement of the articles in the container individual to the fixed ejector, whereby the presence of articles in the last said container will render the pivoted ejector inactive, means tending normally to render the pivoted ejector active, the active faces of said ejectors being substantially in alinement, and means for reciprocating said element, each of the ejectors operating to vend the articles from their respective containers directly to said outlet, and independently of the articles in the other container.

12. A vending machine for holding a plurality of supplies of articles side by side, a delivery outlet, a reciprocable element, a fixed ejector carried with said element, a pivoted ejector also carried with said element, an extension carried by the pivoted ejector and extending into the path of movement of the articles in the container individual to the fixed ejector, whereby the presence of articles in the last said container will render the pivoted ejector inactive, means tending normally to render the pivoted ejector active, the active faces of said ejectors being substantially in alinement, and means for reciprocating said element, all of the articles from one container being completely vended directly to said delivery outlet and in advance of the removal of any of the articles from the other container.

13. A vending machine embodying a plurality of containers for the articles to be vended arranged side by side, ejectors individual to the containers, operating mechanism common to the ejectors, a delivery outlet common to the containers, each of the ejectors operating to vend the articles from their respective containers and directly to said delivery outlet, and means whereby the presence of the articles in one of the containers will render the ejector of the other container inactive, all of the articles from one of the containers being completely vended in advance of the removal of any of the articles from the other container.
